US0D1061412S

(12) **United States Design Patent** (10) **Patent No.:** **US D1,061,412 S**
(45) **Date of Patent:** **** Feb. 11, 2025**

(54) **BATTERY**

(71) Applicant: **ZEBRA TECHNOLOGIES CORPORATION**, Lincolnshire, IL (US)

(72) Inventors: **Mu-Kai Shen**, Taipei (TW); **Andrew Ellis**, Kitchener (CA); **Xinghua Shi**, Milton (CA); **Yanjun Chen**, Shanghai (CN)

(73) Assignee: **Zebra Technologies Corporation**, Lincolnshire, IL (US)

(**) Term: **15 Years**

(21) Appl. No.: **29/841,067**

(22) Filed: **Jun. 2, 2022**

Related U.S. Application Data

(63) Continuation of application No. 29/745,640, filed on Aug. 7, 2020, now Pat. No. Des. 957,321.
